QUICK-CHANGE INTERNAL STRUCTURE FOR HANDBAGS

Filed Nov. 15, 1945

UNITED STATES PATENT OFFICE

2,464,312

QUICK-CHANGE INTERNAL STRUCTURE
FOR HANDBAGS

Winnie Belle Holden, Columbia, S. C.

Application November 15, 1945, Serial No. 628,733

2 Claims. (Cl. 150—34)

1

This invention relates to a quick-change bag insert and more particularly to an insert for a lady's handbag or similar bag which is provided with a plurality of article holding pockets or recesses and which can be quickly transferred to other bags with its contained articles without the necessity of individually transferring such articles.

In accordance with the present invention, a unitary compact insert member is provided with a plurality of article receiving pockets and is adapted to be placed within the interior of a container such as a lady's handbag. The insert may be constructed of flexible material such as fabric and be provided with stiffening elements covered by the flexible material to hold the insert in a definite position in the bag so that the pockets therein are positioned for the reception and withdrawal of articles usually carried in such bags. The articles held in the insert can each have its individual position so that it can be readily located and provision is also made for retaining miscellaneous, loose articles within the confines of the insert.

The insert is entirely separate from the handbag itself so that it may be easily removed and placed in another similar handbag. That is to say, the owner may have a series of handbags of approximately the same size but of different colors and designs, for example, to match different costumes. The insert with its contained articles may be quickly changed from one of such handbags to another without individually transferring the various articles. In the preferred construction of the insert provision is made for easily removing the stiffening members to enable cleaning of the flexible material of the insert, such as by laundering or dry cleaning.

It is therefore an object of the invention to provide a quick-change bag insert for handbags or other containers which has provision for retaining various articles in definite position and which may be quickly transferred along with its contained articles from one handbag to another.

Another object of the invention is to provide a quick-change bag insert provided with a plurality of pockets for various articles and which is provided with stiffening members for holding the insert in a definite position in the handbag.

A further object of the invention is to provide an insert for ladies' handbags or the like constructed of flexible material mounted upon stiffening members and arranged for easy removal of the stiffening members to provide for cleaning of the insert.

2

Other objects and advantages of the invention will appear in the following description of a preferred embodiment thereof shown in the attached drawings, in which:

5 Figure 1 is an isometric view in vertical section through a handbag containing the insert of the present invention with parts broken away;

10 Figure 2 is a fragmentary horizontal section through one end of the handbag and insert and taken on the line 2—2 of Figure 1; and

Figure 3 is a plan view of the flexible portion of the insert before it has been edge seamed to receive the stiffening members.

15 Referring to the drawings, the insert may include a body portion 10 preferably made of a single piece of flexible material and having a plurality of side wall sections 11, 12, 13 and 14. The side wall sections 11 and 12 may be folded toward each other along a line 16 indicated by a dash-dot line in Figure 3 and may have their edges stitched together as indicated at 17 in Figure 2 to form a pocket for receiving a stiffening member 18. Similarly, the side wall sections 13 and 14 may be folded toward each other 20 along a line indicated by the dash-dot line 19 in Figure 3 and have their edges stitched together as indicated at 21 in Figure 2 to form a pocket for receiving a stiffening member 22. Upon inserting the stiffening members in their respective 25 pockets and folding the body portion 10 along the fold lines 23 and 24 indicated by dash-dot lines in Figure 3, the stiffening members 18 and 22 will be substantially parallel to each other as shown in Figure 1 to form a U-shaped insert 30 when the handbag is closed which insert will open to an approximate V when the bag is opened. The end portions 26 and 27 of the body portion 10 may be overlapped as shown in Figure 1 and 35 may be secured together in any desired manner, for example, by stitching or by the snap fasteners 28 indicated in Figure 3.

40 One or more pockets forming members such as the members 29 and 31 may be suitably secured to the side wall portion 11 of the body member 10, 45 for example, by stitching 32 as indicated by the dotted lines in Fig. 3. Either or both of these members may be divided into a plurality of pockets by intermediate stitching to the side wall member 11 as indicated by the dotted lines 33 of Figure 3. Similar pocket members 34, 35 and 37 may 50 be secured to the side wall sections 12, 13 and 14, respectively, of the flexible body member 10 to form pockets upon each of these sections, the latter section preferably having a second pocket member 38 stitched thereto. As shown in Figures 55

1 and 3, certain of the pocket members may overlap other pocket members, for example, the pocket member 29 may overlap the pocket member 31 and the pocket member 38 may overlap the pocket member 37.

The entire insert may be constructed to have any suitable dimensions to enable it to be positioned within any suitable type of handbag, for example, a handbag having a flexible body portion 39 and a top closure structure including members 41 and 42. The insert is entirely free of the structure of the handbag and may be removed and inserted as a unit so as to be capable of being transferred from one bag to another along with any articles contained in the pockets thereof. It will also be apparent that the insert provides a central space 43 for miscellaneous articles in addition to those contained in the various individual pockets, these miscellaneous articles also being carried by the insert when it is transferred from one bag to another. Also, upon removal of the insert from the bag, the overlapping end portions 26 and 27 of the body portion 10 can be separated so that the stiffening members 18 and 22 can be withdrawn to enable the flexible portion of the insert to be laundered or otherwise cleaned without damage to the stiffening members. These stiffening members may be of any suitable material, for example, sheet material such as cardboard, fiber board or light metal, or may be a wire framework or metal screen, etc.

The insert above described enables all of the articles usually carried in such a handbag to have a definite place thus avoiding searching through the handbag for a desired article. Any suitable arrangement of pockets may be employed, but for purposes of illustration only, the pocket A may contain a toothbrush in its case and a comb and the pockets B, C, D, E, F, G and H may contain soap, aspirin, lipstick, perfume, compact, matches and a carton of tooth powder, respectively. Similarly, the pockets I, J, K, L, M and N may contain an identification card, pencil, pen, darning tube, key case for extra keys and diary, respectively. Also, the pockets O, P, Q, R and S may contain a coin purse, band-aids, apartment key, car keys, and glasses, respectively. In the same manner, the pockets T, U and V may contain a cigarette case, ration and bank books, and individual powder puffs, respectively, while the pocket W may contain letters, road maps, address books, etc. As stated above, miscellaneous articles not adapted for insertion in any of the pockets may be placed in the space 43 between the pocket members 34 and 36. Although the insert chosen for illustration is rectangular in shape so as to fit substantially rectangular handbags, it is apparent that the body member and stiffening members of the insert may be of any suitable conformation and dimension so as to fit bags of different sizes and shapes, for example, square bags,

round bags, triangular bags, etc., without departing from the essentials of the present invention.

While I have disclosed the preferred embodiment of my invention, it is understood that the details thereof may be varied within the scope of the following claims.

I claim:

1. A quick-change bag insert comprising a substantially rectangular body member formed of flexible material, said body member having its end portions folded toward the center of said body member and secured thereto along the edges of said body member to form open pockets, a stiffening member removably positioned in each of said pockets whereby said body member may be folded about its center portion to form upstanding side members, means for releasably closing said pockets for holding said stiffening elements therein while providing for removal of said stiffening elements to enable cleaning of said body member, said side members having elements of flexible material secured to the exposed surfaces of said body member to form a plurality of external pockets for receiving articles to be carried in said bag, said insert being shaped to be received within a handbag while carrying said articles and being transferable with its contained articles from one handbag to another.

2. A quick-change bag insert comprising a substantially rectangular body member formed of flexible material, said body member having its end portions folded toward the center of said body member and secured thereto along the side edges of said body member to form open pockets, a stiffening member removably positioned in each of said pockets whereby said body member may be folded about its center portion to form upstanding side members, said side members having elements of flexible material secured to the exposed surfaces of said body member to form a plurality of pockets for receiving articles to be carried in said bag, said insert being shaped to be received within a handbag while carrying said articles and being transferable with its contained articles from one handbag to another.

WINNIE BELLE HOLDEN.
